UNITED STATES PATENT OFFICE.

LOUIS S. BURBANK, OF BOSTON, MASSACHUSETTS, ASSIGNOR OF ONE-HALF
TO IRVING H. FAY, OF SAME PLACE.

TYING-MACHINE.

SPECIFICATION forming part of Letters Patent No. 515,143, dated February 20, 1894.

Application filed March 16, 1893. Serial No. 466,263. (No model.)

To all whom it may concern:

Be it known that I, LOUIS S. BURBANK, of Boston, in the county of Suffolk and State of Massachusetts, have invented certain new 5 and useful Improvements in Tying-Machines, of which the following is a specification.

This invention relates to a machine for temporarily tying together the two sides of a boot or shoe upper, previous to lasting, so 10 that, when said uppers are stitched or fastened over the last, they will not gape open; and it has for its object to provide a machine of simple construction and rapid operation, which shall be adapted to introduce a string 15 through two of the lace-holes in said upper, and to automatically tie and sever the same from a ball or length of string.

The invention consists in the improved machine for the above-mentioned purposes which 20 I will now proceed to describe and claim.

Of the accompanying drawings, forming part of this specification: Figure 1 represents a side view of my improved tying machine. Fig. 2 represents a top plan view of the same, 25 all but a small portion of the top-plate of the frame being broken away. Fig. 3 represents a front elevation of the same. Fig. 4 represents a section on line 4—4 of Fig. 2. Figs. 5, 6 and 7 represent different positions of the 30 looper at different times in forming the knot. Figs. 8, 9 and 10 represent the string at different stages of the knot-forming operation. Fig. 11 represents a view of the string-guide, being a section on line 11—11 of Fig. 12. Fig. 35 12 represents a section on line 12—12 of Fig. 11. Fig. 13 represents a bottom plan view of a portion of the mechanism hereinafter referred to. Figs. 14, 15, 16 and 17 represent detail views of the looper hereinafter 40 described. Fig. 18 represents a perspective view of the second pair of pinchers. Fig. 19 shows a longitudinal horizontal section, illustrating a take-up mechanism. Fig. 20 shows a detail view, taken on a section line extending longitudinally through a portion of the machine-frame below the lever 26, as viewed in Fig. 19 and looking toward the same. Fig. 45 21 shows a detail to be referred to hereinafter.

The same letters and numerals of reference 50 indicate the same parts in all the figures.

In the drawings: C represents the frame of

the machine, which may be of any suitable form; and A the main shaft of the machine, which is suitably journaled in portions of the frame C near the rear of said frame.

55

g represents the top-plate of the frame of the machine, which is suitably attached to the main portion of the frame C.

E represents a plunger, which slides vertically in a guide E' affixed to the frame C. 50 The lower end of said plunger E is provided with two backwardly-projecting ears E² E², which are adapted to engage the end of a lever h, as shown in Figs. 3 and 4. The said lever h is pivoted at h' to the rear portion of 55 the frame C of the machine, and has a cam-roller h² upon it, which is adapted to run in a groove 2' in one side of a cam 2, the said cam being fixed upon the shaft A and rotated thereby.

The plunger E is located exactly in line with a hole f in the top plate g of the machine, and is adapted to be pushed upwardly through said hole by the lever h, actuated by the cam 2, as above described.

70

B represents a block, which is adapted to slide up and down in guides B' affixed to the frame C near the front portion thereof. The sliding block B is moved up and down on its guides or ways B' on the frame C, by means 80 of a bell-crank lever F, which is pivoted to a boss or block F' on the frame of the machine. One arm of the bell-crank lever F is provided with a cam-roller, which runs in a groove in a cam 5 on the shaft A; and the other arm 85 of said lever is engaged with the lower portion of the sliding block B, as shown in dotted lines in Fig. 3.

From the above it will be readily seen that the sliding block B is moved upwardly and 90 downwardly on its ways B' once in each revolution of the shaft A.

The sliding block B has journaled in it, near its upper end, two short shafts e and e', the said shafts e and e' being in line with 95 each other, and a space being left between their confronting ends for the passage of the tying string. The shaft e' is adapted to rotate in its bearings in the block B, but not to slide therein; and is provided with a pinion 100 k² suitably affixed to it, said pinion being adapted to engage a rack k' on a fixed sup-

port, as hereinafter described. The shaft e' also carries on its inner end the looper a' , the action of which will hereinafter be particularly explained. The shaft e is adapted both to rotate and to slide in its bearings in the block B , and has feathered onto it a pinion k^2 , which is adapted to engage a rack k , as hereinafter described. The shaft e is adapted to be moved endwise by the engagement therewith of one end of a lever d , which is pivoted to a fixed support d' on the frame C . The other end of said lever is provided with a cam-roller, which runs in the groove of a cam 3 on the shaft A . From the form of the groove on the cam 3 , it will be seen that, during one rotation of the shaft A , the lever d will cause the shaft e to move endwise first in one direction and then in the opposite direction, a period of rest intervening between said movements when the said shaft e is in its farthest inward position, or that position shown in Figs. 1 and 2, and another period of rest occurring when said shaft e is at the other extreme of its endwise movement. The pinion k^2 is feathered on the shaft e , so that, when said shaft moves endwise, it may slide through the said pinion and the latter will remain in engagement with the rack k , and at the same time remain in rotative engagement with said shaft e . The shaft e also carries, on its inner end, a string guide b , hereinafter described.

$c' c'$ represent a pair of pinchers, which are pivoted to a stud c^2 . The stud c^2 has one end adapted to slide in a groove or way c^4 formed in one side of the guide-piece or standard E' which supports the plunger E . The under jaw c' of the pinchers is provided with a downward extension c^5 , which slides in a track formed in the main portions or arms c^6 which support the upper jaw. One end of a spring c^7 is attached to and pushes against the lower end of the extension c^5 , and the other end of said spring is affixed to the main portion of the pinchers-frame; the spring c^7 thus tending to keep the jaws $c' c'$ closed upon each other. The main portion of the pinchers-frame has a backwardly-projecting portion t' , which is adapted to be struck by a projection t on the cam 2 , the said contact of the projections t and t' throwing the pinchers forward, as will be readily seen. As the pinchers $c' c'$ are thrown forward, as just described, a projection v on the extension c^5 of the under jaw c' strikes the under side of a trip v' affixed to the standard E' , thus opening the jaws. After the projection v has passed beyond the trips v' , the jaws are again closed by the force of the spring c^7 . When the lug or projection t on the cam 2 passes away from contact with the projection t' on the main portion of the pinchers-frame, the latter is swung backward on its pivot c^2 by the stress of a spring c^8 attached at one end to said pinchers-frame and at the other to the frame of the machine.

s' represents a projection, attached to one

end of a rock-shaft, which is journaled in a bearing in a boss or block x on the frame of the machine. On the other end of said rock-shaft is an arm s^2 , which is adapted to rest upon the upper side of the projecting end of the stud c^2 when the pinchers are in the position shown in Figs. 3 and 4.

s represents a lug or projection on the cam 2 , which is adapted to strike the projection s' , thus causing the rock-shaft to make a partial revolution and causing the arm s^2 upon said shaft to depress the pivot or stud c^2 and the pinchers pivoted thereto from the position shown in said Figs. 3 and 4, the lug s clearing the projection s' when the end of said downward movement is reached. When the pinchers are again raised, as hereinafter described, the arm s^2 is raised also by the stud c^2 , and the projection s' is again brought into the path of the lug s .

The racks $k k'$, before mentioned, are affixed to rigid supports on the frame C . It will be seen, therefore, that, when the sliding block B is moved upwardly or downwardly, the pinions k^2 and k^3 on the shafts e and e' respectively, engaged with said racks, will cause the said shafts to rotate in one direction while the sliding block B is moving upwardly, and in the opposite direction when said block is moving downwardly.

The string-guide b on the shaft e is best shown in Figs. 11 and 12. From these figures it will be seen that the said string-guide is loosely mounted upon the shaft e , the guide being kept in connection with said shaft by means of a spring n , a block or slide a^2 , and a cam n' which is rigidly affixed to the shaft e . The spring has one end attached to the string-guide, and is attached at its other end to a lug or projection a^3 on the block or slide a^2 sliding in ways in said string-guide, the said lug a^3 being pressed against the cam n' by the spring, and having a portion a^9 which interlocks with a projection a^{10} of the cam, thus engaging the string-guide with the shaft e . The block or slide a^2 is provided with a projection or finger b' , which I call the string-guide finger. Said finger is provided at its outer end with a hole a , through which the string is adapted to be threaded.

The looper a' , already mentioned, is best shown in Figs. 14, 15, 16 and 17. In said figures, it will be seen that the looper consists of two parts, the main portion a' being rigidly affixed to the shaft e' , while the plate i^2 is loosely journaled on said shaft, and is kept in connection with the main portion a' of the looper by a spring i^3 , as shown, and a lug i^9 engaging a notch i^{10} in the member a' . The main portion a' of the looper is provided with a shield a^5 , as shown in Figs. 4 and 15. The plate i^2 has attached to it the looper-knob i , as shown in Figs. 4 and 14.

m represents a hook or barb, constituting one member of a second pair of pinchers. The said hook m is attached to the outer member p' of a compound sleeve G . The said com-

pound sleeve G includes an outer member or sleeve p' , and an inner member or sleeve p , journaled on a short shaft D mounted in suitable bearings in the frame of the machine.

5 6 represents a lever, which is pivoted at 6' to a fixed support, and has at one end a cam-roller, which runs in the groove of a cam 4 on the shaft A, and at the other end a cam-roller p^2 , which enters the cam-grooves $o o'$ in the 10 members $p p'$ of the compound sleeve G.

As will be readily understood, the lever 6 imparts to the compound sleeve and to the parts connected thereto a definite movement and a corresponding return movement during 15 each rotation of the shaft A. Beginning when the cam-roll is at the outermost end of the cam-grooves in the compound sleeve G, the inward movement of said cam-roller along said grooves causes both sleeves to turn on 20 their shaft D, thus rotating the devices connected with the said sleeves toward the supporting-plate g. When the roller reaches the end of groove o' , sleeve p' , carrying the barb m, commences to slide longitudinally upon 25 sleeve p . Both sleeves p and p' being connected together by means of a slot m^5 in an extension p^3 of the sleeve p' and a screw m^6 on an extension r^3 of the sleeve p , they continue to rotate until the roller reaches the 30 longitudinal portion of the slot o , when sleeve p ceases its movement and sleeve p' continues its longitudinal movement to the end of slot o , at which point the backward movement of the lever 6 is commenced, the cam 4 being 35 timed in accordance with the grooves $o o'$, as will be readily understood.

m' constitutes the second member of the second pair of pinchers, and is pivoted at r^2 to an arm or support m^2 , which is part of the 40 inner sleeve p of the compound sleeve G. From the movement of said compound sleeve above described, it will be seen that the two members m and m' of the second pair of pinchers are rotated down together, and that 45 the member m , affixed to the outer sleeve p' , is then projected through and beyond the member m' . The sleeve p' is provided with a cam-projection r on its side which is next the member m' , and the latter has a set-screw 50 r' at its outer end. It will be seen that, when the member m is projected in advance of the member m' and again when said member m is retracted to its normal position shown in Fig. 2, the set-screw r' will pass over the cam-projection r and will cause the front or inner 55 end of the member m' to close upon the member m .

The barb m slides in a track made for it in the arm or support to which the member m' is 60 pivotally connected. To the member m' is affixed, just in front of its pivot point, a spring z, as shown in Fig. 18. The barb or hook m is made with a scissors edge at m^3 , and the member m' has a corresponding scis- 65 sors edge at m^4 , so that, when said members are closed upon each other by the action of the cam-projection r upon the set-screw r' , as

before described, they will sever the string. The spring z, being slightly in advance of the member m' to which it is attached, will come 70 down upon the string and hold it firmly against the upper side of the arm or support m^2 . It will be seen that the string is firmly held by said spring z and arm m^2 for a short period before the severing action of the members m and m' , during said action, and for a short period after the same. It is during this last period that the pinchers c and c', holding the other end of the string, move downwardly, thus drawing the knot taut. The loose end 80 of the string, projecting from the string-guide b, is not held by the pinchers $m m'$, the spring z being on one side of the said scissors-blades, namely, the side nearest the front of the machine, said spring only holding the end of the 85 string connected with the knot. After being severed, the loose end projecting from the guide b is withdrawn by the before-described movement of said string-guide, before the knot is drawn taut by downward movement 90 of the pinchers c c', as before described.

The operation of the machine is as follows: The sliding block B being in its lowest position, the end of a ball of string is threaded through the hole a in the finger b' of the 95 string-guide (see Fig. 12). The machine is then threaded and ready to start. The shaft A being rotated, the lug or projection t strikes the cam-projection t' of the pinchers c c', moving said pinchers forward, the pinchers being opened at the same time by engagement of projections v and v'. The string-guide b is at this time in line with said pinchers, and, just before the latter reach the end of their forward movement, the end of the 100 string, projecting through the hole a, comes between the jaws of said pinchers, and the string is therefore grasped by said jaws when they close at the end of their forward movement. The cam-projection t passes away from 105 the projection t' and allows the pinchers to be drawn backwardly by the spring c³, drawing with them a supply of the string through the slot a of the finger b'. The piece of string thus grasped by the pinchers, extending from 110 them through the string-guide finger b', is in a line directly over the line of travel of the plunger E. The cam 2 then operates the lever h, causing the plunger to ascend through the hole f in the plate g. The top of the plunger 115 is grooved, and comes in contact with the string in its upward movement, carrying said string with it upward through the hole f. The plunger is then in the position shown in the drawings. When the plunger has come up, as 120 described, all cams rest long enough to enable the operator to place a boot upper over said plunger, allowing the plunger to project through two of the lace-holes in said upper, the edges of the upper being toward the front, 125 as shown in Figs. 5, 6 and 7, in which u u is the upper. In this upward movement of the string and plunger, to save the string from 130 running over the end of the plunger, the

pinchers $c c'$ holding one end of the string are permitted to rise to the position shown in the drawings, by the action of the plunger, the path of travel of said pinchers being indicated by the dotted line w in Fig. 4. The plunger pulls sufficient string through the hole a in the string-guide to permit its described movement. The shaft e is then moved still farther inward by the lever d , carrying the string-guide finger beyond the path of the looper-knob i . The bell-crank lever F , actuated by the cam 5, then begins to move the sliding block B upwardly, and the fixed racks $k k'$, engaging the pinions $k^2 k^3$, cause the shafts $e e'$, journaled in said block, to revolve. The revolution of the shaft e' causes looper a' and the looper-knob i to travel in the path shown by the dotted line q in Fig. 3. The first direction of the looper and looper-knob is downward, crossing the string, the shield a^5 on the looper a' striking the string and throwing it over so that the looper-knob hooks over said string, and its further revolution carries the string with it. The string-guide b is then moved outwardly, or toward the left, by means of the lever d , acting on the shaft e to which said guide is attached, the shaft at the same time rotating and carrying the string-guide with it. It will thus be seen that the string may pass between the looper and guide, as shown in Fig. 6, and also through the space between the confronting ends of the shafts $e e'$. As the looper thus revolves, it forms a loop on the knob i . The shafts e and e' continue to revolve as the block B rises, until the looper-knob i strikes the top of the plunger E , and the side l of the string-guide b (see Fig. 11) strikes the upper which is engaged with said plunger. When the looper-knob i strikes the top of the plunger, it stops and the looper a' continues to revolve, carrying the loop formed on the knob i down over the plunger. When the side l of the string-guide strikes the upper, the guide stops, and the shaft e still continues to revolve, the cam n' on said shaft moving the block a^2 , carrying the string-guide finger away from it, thus carrying the string beyond the plunger (see Fig. 7). It will be seen that the block B , sliding in its diagonal or sloping track, carries the looper and looper-knob and the string-guide up to the plunger E , so that, when the loop is formed by the revolution of the knob, said knob swings over the plunger and strikes the upper end of the same, dropping the loop over said plunger and the bight of string supported thereby, the looper a' carrying the said loop downwardly after the looper-knob has struck the plunger, as described. The cam 4 then moves the lever 6 to operate the compound sleeve G , and the said devices, operating as already described, project the hook m , the said hook passing between the plunger and string, as shown in Fig. 7, and then retract said hook, carrying with it the string carried across its path by the before-described movement of the string-guide b , the other member

m' of the second pair of pinchers closing upon the hook m and severing the string and holding the end between the members m^2 and z , as described. At the same time as the second pair of pinchers m^2 and z , holding one end of the string, are retracted, the first pair of pinchers $c c'$, holding the other end of the string, are caused to move downwardly by the engagement of the projection s on the cam 2 with the projection s' , as already described. At the same time, the plunger E , actuated by the lever h , is retracted, the cam 2 being timed accordingly. It will thus be seen that the knot formed on the string is drawn taut. The pinchers $c c'$, holding the string between them by spring-pressure, will let said string slip when the knot has reached its proper tension. As soon as the string is cut, as above described, the block B begins to move downwardly, carrying the loose end of the string with it. The hole a in the string-guide finger b is provided at one end with a tension b^2 , which prevents the loose end of the string from slipping back through it. As the block B begins to slide downwardly, the shafts e and e' rotate in the opposite direction from that in which they rotated during the upward movement of said block. As this backward rotation commences, the main portion a' of the looper rejoins the plate i^2 carrying the knob i , the two being brought together again by means of the spring i^3 . The string-guide b also resumes its normal position on the shaft e soon after the commencement of the said backward rotation, the spring n acting on the cam n' to bring about the desired result, as will be readily seen.

The plunger E is preferably made, as shown in Figs. 3 and 4, with a slight overhang at its forward side, so as to adapt it to hold the string a little in front of its side and allow room for the entrance of the hook m between the said string and plunger.

The main driving-shaft A of the machine may be driven by any suitable means, as by a crank, or belt and pulley, or in any other suitable way.

20 represents an adjustable tongue, over which the loop is tied when it is desirable to have more play in it, when the uppers are unfolded and placed upon the last (see Fig. 21).

Referring to Figs. 19 and 20, 21 designates a hole in the base of the machine, through which the string 25 is supplied. 22 is a block, between which and the spring 23 the string 25 is held fast when the spring 23 is released by the lip 24 of the bell-crank lever 26, which is actuated by the superior spring 27 and the side cam-projections on cam 5.

During the revolution of the looper i^2 , more string is drawn from the supply than is needed in the knot, and, as the knot is being tied, the first rise 28 of the cam 5 actuates the lever 26, throwing the end bearing the string-eyelet 29 back, releasing the spring 23, which immediately holds the string 25 fast between

itself and the block 22 and takes up the slack from the loop. When the knot is tied and the string cut, the end left projecting from the finger b' is unnecessarily long and the 5 second projection 30 on the cam 5 throws the lever 26 into its return position, drawing the string back through the finger b' until it projects suitably. The lever then returns to its original position, leaving the string free to 10 feed.

Having thus described my invention, what I claim as new, and desire to secure by Letters Patent, is—

1. A machine of the character described, 15 comprising in its construction a plunger adapted to take the string through the article under treatment, a movable string-carrier or looper having normal position on that side of the article which the plunger enters, means 20 for moving said carrier to the other side of the article, and means for forming a knot of the bight held by the plunger and that brought to it by the carrier.

2. A machine of the character described, 25 comprising in its construction a plunger adapted to take the string through the article under treatment, a string-holder or guide, a movable grasping device adapted to take an end of the string projecting from the holder 30 or guide and draw it across the path of the plunger, a movable string-carrier or looper having normal position on that side of the article which the plunger enters, means for moving said carrier to the other side of the 35 article, and means for forming a knot of the bight held by the plunger and that brought to it by the carrier.

3. A machine of the character described, 40 comprising in its construction a vertically-movable plunger adapted to engage the string, a vertically-movable grasping-device arranged to take the string and draw it across the path of the plunger and to be elevated with the plunger by means of the string, a 45 looper arranged to carry the string from one side of the article under treatment to the other, and means for forming a knot, substantially as described.

4. A machine of the character described, 50 comprising in its construction a vertically-movable plunger adapted to engage the string, spring-closed grasping-jaws to take the string and draw it across the path of the plunger, means for automatically opening said jaws, 55 a looper to take the string from one side of the article under treatment to the other, and means for forming a knot in the string, substantially as described.

5. A machine of the character described, 60 comprising in its construction a vertically-movable plunger, a pivoted grasping-device arranged to draw the string across the path of the plunger, a cam for actuating said grasping-device in one direction, a spring to actuate it in the opposite direction, a looper to 65 carry the string from one side of the article under treatment to the other, and means for

forming a knot in the string, substantially as described.

6. A machine of the character described, 70 comprising in its construction a carrier to take the tying string through the article under treatment, a vertically-movable grasping-device for holding one end of the string, a looper to carry the string from one side of the 75 article to the other, means for forming a knot in the string, a second grasping-device, and means for depressing the first grasping-device after the knot is formed.

7. A machine of the character described, 80 comprising in its construction a plunger adapted to take the string through the article under treatment, a rotary string-carrier or looper having normal position on that side of the article which the plunger enters, means 85 for moving said carrier to the other side of the article and rotating it during such movement, and means for forming a knot of the bight held by the plunger and that brought to it by the carrier.

8. A machine of the character described, comprising in its construction a plunger arranged to carry the string through the article under treatment, a rotary string-guide, a rotary looper co-acting with said string-guide, 95 and arranged to carry the string from one side of the article to the other, and means for forming a knot in the string, substantially as described.

9. A machine of the character described, 100 comprising in its construction a pair of shafts arranged end to end with a space between their confronting ends, a string-guide carried by one of said shafts, a looper carried by the other shaft, a plunger to take the string 105 through the article under treatment, means for moving the two shafts and rotating the string-guide and looper whereby the string is carried from one side to the other of the article under treatment and a loop formed, and 110 means for forming a knot in the string, substantially as described.

10. A machine of the character described, 115 comprising in its construction a plunger arranged to carry the string through the article under treatment, a rotary and longitudinally-movable string-guide, a rotary looper co-acting with said string-guide and adapted to carry the string from one side of the article to the other, and means for forming a knot in the 120 string, substantially as described.

11. A machine of the character described, 125 comprising in its construction a plunger arranged to carry the string through the article under treatment, a rotary and longitudinally-movable string-guide, a rotary looper co-acting with said string-guide and arranged to form a loop and carry the same over upon the bight of string held by the plunger, and means for forming a knot in the string, substantially as 130 described.

12. A machine of the character described, comprising in its construction a plunger arranged to carry the string through the article

under treatment, a string-guide having a sliding finger which holds the string, a rotary looper co-acting with said guide to form a loop and carry the same over upon the bight 5 of string held by the plunger, and means for forming a knot in the string, substantially as described.

13. A machine of the character described, comprising in its construction a plunger arranged to carry the string through the article under treatment, a rotary looper composed of two members yieldingly held together, one of them having a looper knob arranged to come upon the plunger and the other arranged to 15 push the loop off the said knob and over the plunger, and means for forming a knot in the string, substantially as described.

14. In a machine of the character described, the combination of a string-guide adapted to 20 carry a string, a grasping-device for pulling said string therefrom, a plunger adapted to carry a length of said string through the lace-holes in the upper of a boot or shoe, a top-plate or work-support adapted to support an 25 upper in position, a rotary looper adapted to co-operate with the said string-guide in forming a loop and in passing said loop over the bight of the string supported by the plunger, and a hook adapted to pass through said 30 bight and draw the string therethrough, thus forming a knot and fastening together the two sides of the upper, as set forth.

15. In a machine of the character described, the combination of a string-guide, adapted to 35 carry a string; a pair of pinchers, adapted to be projected and opened, and then closed and retracted to grasp said string and pull a portion from said string-guide; a plunger, adapted to move vertically and to engage the string; 40 a top-plate or work-support adapted to support the upper of a boot or shoe; a rotary looper, adapted to co-operate with the said string-guide in forming a loop in said string, and to pass said loop over the bight of the string supported by the plunger; a hook, 45 adapted to pass through said bight and draw the string therethrough, thus forming a knot and fastening together the two edges of the upper; and a cutter, adapted to cut said string 50 so drawn through the bight by the said hook, as set forth.

16. In a machine of the character described, the combination of a rotary string-guide mounted on a shaft and adapted to carry a 55 string, a rotary looper mounted on a shaft, pinions on said shafts, a sliding block in which said shafts are journaled, fixed racks engaging the pinions, pinchers adapted to be projected and opened and then closed and re- 60 tracted to grasp and pull out a portion of said string, a plunger moving vertically and having its upper end adapted to engage said

string, a top-plate or work-support for the upper of a boot or shoe, a hook adapted to be projected through the bight of string on the 65 plunger and to draw the string through said bight, and a grasping and cutting device adapted to grasp the end of the string thus drawn through the bight and to sever the same, retaining the severed end of the string 70 until the knot is drawn taut, as set forth.

17. In a machine of the character described, the combination of a string-guide, a pair of pinchers adapted to pull a string out of said guide, a plunger adapted to carry a bight of 75 the string upwardly through an orifice in a work-support, a looper adapted to make a loop in said string, a sliding block, as B, sliding in a diagonal track in the front of the machine, said block carrying the said string-guide and looper and being adapted by its diagonal track to carry said parts over the said plunger during their operative movement and back from said plunger during their receding movement, as set forth. 80

18. In a machine of the character described, the combination of a string-guide, a pair of pinchers adapted to grasp and pull out a length of string, a plunger adapted to carry a bight of string upwardly through a hole in 90 the top-plate or work-support, a rotary looper composed of two parts having a spring connection between them, one of said parts being adapted to form a loop in the string and the other to force said loop down over the 95 bight of the string supported by the plunger, a shaft on which said looper is mounted, and a sliding block in which the said shaft is journaled, as set forth. 85

19. A machine of the character described, comprising in its construction a plunger arranged to carry the string through the article under treatment, a rotary string-guide, a rotary looper co-acting therewith and adapted to form a loop and deposit it over the bight 105 of string on the plunger, a longitudinally-movable hook arranged to draw the string through the bight on the plunger, and a grasping-device co-acting with said hook, substantially as described. 110

20. In a tying machine, a take-up mechanism, comprising a spring arranged to hold the string, a lever engaging said spring, a superior spring acting against the lever, and a cam-wheel adapted to move said lever against the 115 said superior spring.

In testimony whereof I have signed my name to this specification, in the presence of two subscribing witnesses, this 11th day of March, A. D. 1893.

LOUIS S. BURBANK.
